UNITED STATES PATENT OFFICE.

EDWARD F. MILLARD, OF WATERTOWN, MASSACHUSETTS.

METHOD OF DRESSING WOOD-PULP-GRINDING STONES.

1,118,671.

Specification of Letters Patent.

Patented Nov. 24, 1914.

Substitute for application Serial No. 535,531, filed December 29, 1909. Forfeited and renewed as Serial No. 737,130, filed December 16, 1912. This application filed October 17, 1914. Serial No. 867,099.

To all whom it may concern:

Be it known that I, EDWARD F. MILLARD, a citizen of the United States, and resident of Watertown, county of Middlesex, State of Massachusetts, have invented an Improvement 5 in Methods of Dressing Wood-Pulp-Grinding Stones, of which the following description, in connection with the accompanying drawings, is a specification, like letters

10 on the drawings representing like parts.

This invention is a method of uniformly developing the grit on the flat faces of lengthwise extending, peripheral ribs formed on stones for grinding wood into pulp for 15 use in the manufacture of paper, particularly news-paper, and for forming, alternately with such ribs, lengthwise extending grooves that form channels for the lateral escape of the pulp from the stones during 20 the grinding operation.

In the accompanying drawings, Figure 1 is a partial elevational view of the periphery of a pulp grinding stone dressed or fashioned according to my method; Fig. 2 is a partial 25 end elevation of the stone shown in Fig. 1; Fig. 3 is an elevation of the plain-surfaced grinding stone, with a smooth roll extending across the periphery of the grinding stone and adapted to be rotated therewith.

30 This view illustrates the first step in my new method. Fig. 4 shows the grinding stone after its surface has been subjected to the smooth roll shown in Fig. 3, and also shows, extending across the periphery of the grinding stone, a fluted bush-roll adapted to be rotated with the grinding stone and to effect the second and final step of my method, which consists in the formation of the alternating flat-topped grinding ribs in the periphery 35 surfaces of which the grit is uniformly developed, and the grooves that carry away the pulp during the grinding operation; and Fig. 5 is an end elevation of the form of the bush-roll used.

40 In accordance with this invention, after the grinding stone α has been first turned down peripherally to adapt it to frame-containing wood pockets in a grinding machine (not shown), the turned-down peripheral surface is smoothed by the use of a smooth-surfaced roll γ extending across the periphery of the grinding stone and rotated in connection therewith to literally crush down all 45 the high points naturally or normally in the peripheral surface of the trued or turned-

down stone α . This bush-roll is of steel or other hard metal, and has a smooth surface. The grind-stone α and the smooth roll γ , each of which has a length greater than the thickness of the grinding stone, from side to side of the latter, are rotated for a sufficient length of time to develop the grit of the stone uniformly around its periphery and from side to side of the stone.

50 I am aware that it is old to true grinding stones by rotating them one against another with their peripheries in contact. But such an operation necessarily develops high points and indentations on the peripheral surface of each stone, because every stone has some hard spots and some soft spots, and the hard spots or points of one stone will always indent the soft spots of the stone in contact. The purpose of running one grind-stone peripherally in contact with another is not to develop the grit of either stone uniformly but, on the contrary, to true the grind-stones and to develop relatively high and low points in order to cause the grind-stones to cut or grind by the action of the high points on tools presented. In the present instance, the object of subjecting the trued periphery of the stone to the hard, smooth roll γ is to crush down all the high points to the level of the low and relatively 55 soft points, and to obtain clear across the peripheral face of the stone a uniform or uniformly level development of the grit. In this way I obtain a grinding surface of uniform grit before transversely fluting or grooving the broken-down surface of the stone. In Fig. 4 this fluting or transverse ribbing of the stone is obtained by rotating the grind-stone, trued as shown in Fig. 3, in contact with a steel bush-roll α provided with alternating lengthwise-extending peripheral teeth and grooves. The teeth and grooves are so formed that the ribs 2 of the grind-stone are left with their tops flat and characterized by the uniformly developed 60 grit already described. The grooves 3 between the ribs 2 serve to carry off the pulp laterally of the stone during the grinding operation. The bush-roll α is of a length that exceeds the width of the stone α , so that the alternating ribs and grooves are uniformly produced and extend from one side to the other of the stone. The length of the bush-roll should at least equal the width of the stone. It is essential that the stone α 65

and the smooth roll y (Fig. 3) be rotated at the same surface speed in order to crush down the high points uniformly and that the smooth roll be kept in rotation through this step, for if the rotation of the smooth roll be arrested, and the stone allowed to rotate against the bush-roll while at rest, the surface of the stone will be glazed instead of having its grit developed. Wood pulp 10 grinding stones the peripheries of which are thus formed can be used for the production of a finely ground pulp of unique character in respect of uniform fineness and improved quality especially desirable in the manufacture of all fiber news-paper. The pulp produced is of a uniform fibrous character, and when passed through any proper paper-making machine is converted into paper of uniform strength, of soft surface and of a 15 minimized degree of brittleness, without incorporation of sulfite or other strength-giving material. Such paper is strong enough to run through high-speed paper machines, and the paper itself is strong 20 enough to be run through high-speed printing presses. The ridges 2, as stated, are flat-surfaced or topped, and are preferably disposed three to the inch, around the periphery of the grinding stone. I am not aware that any pulp grinding stones have 25 ever been dressed with continuous transverse, alternating ribs and grooves, nor am I aware that any one, prior to my invention.

has ever developed or attempted to develop the peripheral grit of the stone uniformly 35 by crushing the natural or normal high spots or points of the stone to the level of the soft spots.

Having described my invention, what I claim as new and desire to secure by Letters 40 Patent is:

The method of dressing the periphery of a wood pulp grinding stone, consisting in first crushing the high spots or points of the peripheral surface of a trued stone to 45 the level of the low points or spots by continuous rotation of the surface of the stone and a therewith contacting smooth roll at equal surface speeds and thereby developing the grit uniformly across and around the 50 periphery of the grinding stone; and secondly, in transversely and uniformly grooving and ribbing the leveled periphery of the stone from edge to edge to form a uniform series of transverse flat-topped ribs for 55 grinding the wood and an alternating series of transverse grooves for escape of the ground pulp.

In testimony whereof, I have signed my name to this specification, in the presence of 60 two subscribing witnesses.
